UNITED STATES PATENT OFFICE.

PAUL A. MOBERG, OF CHICAGO, ILLINOIS.

DOUBLE ENVELOP.

1,356,872.

Specification of Letters Patent. Patented Oct. 26, 1920.

Application filed February 15, 1918. Serial No. 217,447.

To all whom it may concern:

Be it known that I, PAUL A. MOBERG, a citizen of the United States, residing at Chicago, in the county of Cook and State 5 of Illinois, have invented a certain new and useful Double Envelop, of which the following is a specification.

The present invention relates to envelopes, and more particularly to that class known 10 as double or return envelopes.

The object of this invention is to provide an envelop which is formed with two compartments capable of being separated without destroying either compartment and each 15 having a flap with one of the flaps adapted to secure the compartments together without destroying the flap of the other compartment; and to provide an envelop embodying these characteristics and which 20 may be formed from a single blank and requiring but relatively few folds or flaps.

Various other objects and advantages of this invention will be in part disclosed, and in part become apparent, from the following 25 detailed description of the present preferred embodiment, the same being illustrated in the accompanying drawing, wherein:

Figure 1 is a plan view of a blank constructed according to the present invention and from which a double envelop embodying the features of this invention may be formed.

Fig. 2 is a rear side elevation of the blank 35 having its several flaps folded to form the two compartments and with one compartment closed and the other left open, the dotted lines showing the positions of the folded flaps.

Fig. 3 is a face view of the envelop.

Fig. 4 is a longitudinal section taken through the envelop substantially on the plane indicated by the line 4-4 in Fig. 2, showing both flaps in partly open position.

Fig. 5 is a similar view taken substantially on the plane indicated by the line 5-5 in Fig. 2, showing a section through one end of the double envelop.

Fig. 6 is an enlarged transverse section 50 through the envelop folded and sealed.

Fig. 7 is a perspective view of the completed envelop, on a reduced scale, closed.

In the present embodiment of this invention, as illustrated in the accompanying 55 drawing, the envelop is formed from a blank which is provided with a body por-

tion substantially rectangular in form and divided by a crease line 10 into a front wall 11 at one end of the blank which will be hereinafter referred to as the upper end, 60 and a rear wall 12 at the lower end of the blank. Opposite the front wall section 11, the blank is provided at its lateral edges with back wall flaps 13 and 14 adapted to be folded over against the front wall 11 65 with their free ends overlapping, as shown in Fig. 2, and provided at their lower marginal edges with attaching strips 15 integral with the blank and adapted to be folded over against the inner sides of the flaps and 70 to be secured by an adhesive or the like to the bottom of the front wall 11.

The strips 15 form the bottom edge of an upper compartment which is adapted to be closed at its top by a main flap 16 supplied 75 with an adhesive upon its inner surface for closing the double envelop after the contents have been placed therein.

The lower end of the blank is provided, opposite the rear wall 12 with side flaps 17 80 which are integral with the lateral edge portions of the blank and are adapted to be folded over upon the wall 12 at the same side of the blank at which the flaps 13 and 14 are folded over. The strips 15 of the 85 upper flaps are stamped partly from the lower flaps 17 as shown in Fig. 1 and extend only part way into the lower flaps to provide projections 18 at the upper edges of the flaps 17 adapted to insure the closing of 90 the upper corners of a lower compartment which is formed between the flaps 17 and the rear wall 12.

The blank is provided at its lower end with a front wall flap 19 adapted to be folded upward against the rear wall 12 over the side flaps 17 and secured thereto by an adhesive or the like for completing the lower compartment. This front wall flap 19 carries a sealing flap 20 which is adapted to 100 be initially folded back against the rear wall 19 at the exterior side of the latter, and which is provided with an adhesive upon its outer face for securing the flap 20 to the rear wall 12 when the latter is separated 105 along the crease line 10 from the upper part 11 of the blank.

When the envelop blank is folded to form the upper and lower compartments as above outlined, it presents the form shown in 110 Figs. 2 to 5 inclusive. Mailing matter may be placed in either one or both of the com-

partments and with an address placed upon the exterior face of the front wall 11 of the upper compartment, as shown in Fig. 3, at one side of the double envelop, and the name and address of the sender may be placed upon the front wall 19 of the lower compartment and on the opposite side of the double envelop.

The lower compartment may be now 10 swung up upon the crease line 10 against the rear side of the upper compartment, in which position the lower edge portion of the lower compartment is placed against the upper edge portion of the upper compartment, and the flap 16 may be turned over and secured to the upturned lower edge portion of the lower compartment to hold the compartments together as shown in Fig. 6. When the envelop is so folded the front 20 wall 19 of the lower compartment faces inwardly and the parts are securely retained in this position for transportation through the mails or the like.

When the folded envelop reaches its destination, the flap 16 may be torn open to 25 free the two sections and admit access to both of them. For returning an answer to the sender of the envelop the upper part of the blank is severed from the lower part 30 along the line 10, and the flap 20 of the lower compartment may then be folded over the upper edge of the rear wall 12 and sealed against the exterior face thereof. This lower section thus provides an independent envelop and may be remailed as 35 such, the address of the original sender being placed upon the exterior face of the front wall 19.

The shoulders 18 of the side flaps 17 ef-

fectually close the upper corners of the 40 lower compartment and render it difficult for the introduction of an implement for fraudulently releasing the sealing flap 20. It may also be noted that the upper edges 45 of the side flaps 13 and 14 of the upper compartment are of the full height of the front wall 11 for effectually closing the space beneath the sealing flap 16, and that the outer end portions of the flaps 13 and 14 are reduced in width to facilitate opening of the 50 upper compartment.

It is of course understood that the features of this invention may be embodied in various other forms, the changes and modifications being restricted only by the scope 55 of the following claim.

What is claimed is:

A double envelop comprising a single blank having a main body portion divided transversely into three sections and with 60 one end section equipped with lateral flaps adapted to be folded over said end section and secured to each other, said end section having a closure flap at its free edge and said flaps each having a closure strip at its 65 bottom edge, the intermediate section of the blank having a second pair of lateral flaps adapted to be folded inwardly against the intermediate section and the other end section being adapted to be folded over upon 70 said second pair of flaps, said second end section having a sealing flap at its free edge adapted to be folded between the end sections when the envelopes are turned over one upon the other and adapted to seal the adjacent envelop when the envelopes are severed 75 one from the other.

PAUL A. MOBERG.
